CLAIM

I claim the ornamental design for a wristguard, as shown and described.

DESCRIPTION

FIG. 1 is a front right perspective view of a wristguard showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a side sectional view thereof, taken along line 8-8 of FIG. 6; and,

FIG. 9 is a front right perspective view thereof, shown in condition of use.

The broken line showing is for the purpose of illustrating portions of the article that form no part of the claimed design. The broken line illustrating a hand in FIG. 9 shows environmental structure that forms no part of the claimed design.
